UNITED STATES PATENT OFFICE.

MAURICE LACHMAN, OF NEW YORK, N. Y., ASSIGNOR TO ELECTRO STEEL PRODUCTS CORPORATION, OF NEW YORK, N. Y., A CORPORATION OF NEW YORK.

GRATING.

Application filed April 22, 1920. Serial No. 375,655.

To all whom it may concern:

Be it known that I, MAURICE LACHMAN, a citizen of the United States, and a resident of New York, in the county of New York and State of New York, have invented certain new and useful Improvements in Gratings, of which the following is a specification.

My invention relates to gratings and more particularly to metallic gratings adapted to 10 cover a space or opening provided for light or ventilation purposes.

The object of the invention is the construction of a grating of simplicity of construction and of great strength.

15 A further object of the invention is the production of a grating so constructed as to have a minimum of dirt or dust accumulating space.

The invention consists in the improved 20 construction of grating hereinafter more particularly described and then specified in the claims.

In the accompanying drawing:

Fig. 1 is a perspective view of my improved grating showing the parts assembled.

Fig. 2 is a perspective view of the grating showing two of the transverse members disassembled.

30 Referring to the drawing:

My improved grating consists of a plurality of intersecting longitudinal and transverse members, I-shaped in cross-section, the webs and upper and lower transverse heads or flanges of the longitudinal members being indicated at 1 and 2 respectively and the webs and upper and lower transverse heads or flanges of the transverse members at 3 and 4 respectively. As illustrated, the inner surfaces 5 and 6 of the heads or flanges 2 and 4 adjacent and meeting their respective webs, are inclined thereto so that when the members are assembled to form the finished grating, dust or dirt which would ordinarily accumulate on said inner surfaces 5 and 6 slides or rolls therefrom.

The upper and lower heads or flanges 2 of the longitudinal members are mitered out as at 7 from the edges of said heads or flanges to the webs 1 and the upper heads or flanges and lower heads or flanges are slotted alternately as at 8 and 9 (see Fig. 2) respectively in line with the apex of the mitered portions, said slots extending downwardly or upwardly as the case may be in

the webs 1 of the longitudinal members. Likewise both the upper and lower heads or flanges 4 of the transverse members are mitered out as at 10, said transverse members being provided with slots 11 in line with the apex of the mitered portions, said slots 11 extending in the webs 3 of said transverse members.

The mitered portions 7 and 10 are of a size and their sides are at an angle which permits them to snugly and tightly engage each other when the parts are assembled and the slots 8, 9 and 11 are of a width equal to the thickness of the webs 1 and 3 of the longitudinal and transverse members, so that the 65 webs will enter said slots when the parts are intermeshed and assembled. Also, the depth of said slots 8, 9 and 11 is such as to permit the heads or flanges of the longitudinal and transverse members to lie respectively in the 70 same plane when the members are in assembled position as shown in Fig. 1. When so assembled it will be noted that the heads or flanges of the members at the tops and bottoms thereof closely interfit and engage each 75 other as has been explained and provide strengthening members for the grating and act as reinforcements for the webs of the members to prevent them from being bent or twisted or distorted when subjected to 80 strains or pressure applied in any direction. It will also be apparent that the slotting of the longitudinal members alternately at the tops and bottoms as at 8 and 9, throughout their lengths at spaced intervals 85 for the reception of the transverse members, instead of providing all the slots of the members at their tops or at their bottoms, not only acts to distribute the slight loss of strength of said longitudinal members, due 90 to the slotting, evenly therethrough, but acts to enhance the locking feature of the members of the finished grating and thereby the 95 securesness thereof due to the fact that the transverse members are intermeshed with 100 the longitudinal members alternately from the tops and bottoms of said longitudinal members.

While I have shown but two longitudinal and two transverse members in Fig. 1 and 105 three transverse members in Fig. 2 it will be understood that as many members are employed and intermeshed with each other as are required to produce a grating of the desired size. In assembling the members, as 110

many of the longitudinal members as are required are first placed, spaced apart the required distance and in parallelism, on their edges on a suitable table or support and the required number of transverse members are intermeshed with the longitudinal members by pressing or forcing the same downwardly with the slots 11 engaging the webs 1 and the slots 8 engaging the webs 3 and the mitered portions of the upper and lower heads or flanges of both members engaging each other until the upper and lower flanges respectively lie in the same plane. The structure thus produced is turned completely over and the additional transverse members required are intermeshed with the longitudinal members in the same manner at the slots 9.

What I claim as my invention is:

1. A grating comprising integral longitudinal members and integral transverse members intermeshed with each other and having upper and lower transverse heads or flanges having flat outer surfaces respectively lying in the same plane.
2. A grating comprising a plurality of integral longitudinal members and integral transverse members each consisting of a web terminating along each longitudinal edge in a transverse head or flange, said members intermeshing with each other with the transverse heads or flanges engaging each other and lying in the same plane.
3. A grating comprising a plurality of longitudinal members and transverse members intermeshing with each other and each consisting of a web terminating along each longitudinal edge in a transverse head or flange having inner inclined surfaces adjacent the web and meeting the same.
4. A grating comprising longitudinal members and transverse members each consisting of a web terminating along each longitudinal edge in an upper and lower transverse head or flange connected with the web by an inclined surface and provided with slots cut in the web and the head or flange, said members intermeshing with each other

with the slots in one member engaging the web of the other member and the upper and lower heads or flanges of both members respectively lying in the same plane.

5. A grating comprising longitudinal members and transverse members each consisting of a web terminating along its longitudinal edges in an upper and lower transverse head or flange, said longitudinal members being provided with slots cut in their webs and upper heads or flanges and in their webs and lower heads or flanges and said transverse members being provided with slots cut in their webs and one of their heads or flanges, said members intermeshing with each other with the slots in the longitudinal members engaging the webs of the transverse members and the slots in the transverse members engaging the webs of the longitudinal members and the upper and lower heads or flanges of both members respectively engaging each other and lying in the same plane.

6. A grating comprising longitudinal members and transverse members each consisting of a web terminating along its longitudinal edges in an upper and lower transverse head or flange, said heads or flanges being mitered out from the edges thereof to the webs at spaced intervals and provided with slots cutting through the apex of the mitered out portions and extending into the webs of the members, said members being intermeshed with each other with the slots in one member engaging the web of the other members, the mitered out portions interfitting and engaging each other and the upper and lower heads or flanges of both members respectively lying in the same plane.

Signed at New York in the county of New York and State of New York this 16th day of April A. D. 1920.

MAURICE LACHMAN.

Witness:

IRENE LEFKOWITZ.
